UNITED STATES PATENT OFFICE.

GEORGE T. FIELDING, OF BRIDGEPORT, CONNECTICUT, ASSIGNOR TO GENERAL ELECTRIC COMPANY, A CORPORATION OF NEW YORK.

DESIGN FOR CASING FOR ELECTRIC FAN MOTORS.

Application filed December 7, 1928. Serial No. 29,144. Term of patent 14 years.

To all whom it may concern:

Be it known that I, GEORGE T. FIELDING, a citizen of the United States, residing at Bridgeport, in the county of Fairfield, State of Connecticut, have invented a new, original, and ornamental Design for Casing for Electric Fan Motors, of which the following is a specification, reference being had to the accompanying drawing, forming a part thereof.

The drawing shows in perspective view the front and side of the ornamental casing for electric fan motors of my invention.

I claim:

The ornamental design for casing for electric fan motors substantially as shown.

In witness whereof, I have hereunto set my hand this twenty eighth day of November, 1928.

GEO. T. FIELDING.
